UNITED STATES PATENT OFFICE.

ANTONIO C. PESSANO, OF PHILADELPHIA, PENNSYLVANIA, ASSIGNOR TO
THE GEORGE V. CRESSON COMPANY, OF PENNSYLVANIA.

DESIGN FOR A FLOOR-STANDARD FOR SHAFTING.

SPECIFICATION forming part of Design No. 32,813, dated June 12, 1900.

Application filed May 15, 1900. Serial No. 16,830. Term of patent 14 years.

To all whom it may concern:

Be it known that I, ANTONIO C. PESSANO, of the city and county of Philadelphia, in the State of Pennsylvania, have invented a new and original Design for a Floor-Standard for Shafting, of which the following is a specification.

My new and original design for floor-stands for shafting is shown in the accompanying drawings, in which—

Figure 1 is a front elevation of a standard embodying the design. Fig. 2 is a side elevation of the same. Fig. 3 is a plan view, and Fig. 4 is a vertical sectional view on the line 15 4 4 of Fig. 1.

The design resides in the new and original shape or form which is shown in the drawings.

From a flat base A, which is widened at the ends at α α , extend the upwardly-directed 20 sides B B, inclining toward one another and uniting in an annular frame C. A rib b extends centrally along the outer surfaces of the sides B B and over the annular frame C, which is surmounted at the top by a boss c.

25 D D are enlargements on the outer surface of the sides B B, adjacent to the points at which they are merged into the annular frame C, and these enlargements carry projecting bosses d. A web E, having openings e e, extends between the inner faces of the sides B B

in the central vertical plane thereof and has a rectangular box-shaped portion II, having the transverse rectangular opening or compartment through it, as indicated at F, at the middle of the lower portion of the annular frame 35 C and of approximately the width thereof. Vertical webs f extend on each side of the web E from this box portion F to the base A. The compartment F connects with the interior of the annular frame A by a vertical aperture h. 40

The distinguishing features of the design are the annular frame C, connected by the inclined sides B with the base A and having the webbed space between said parts provided with a box-shaped frame II, forming a compartment immediately below the bottom of the annular frame and communicating with the interior thereof by a vertical aperture. 45

What I claim as new, and desire to secure by Letters Patent, is as follows:

The design for a floor-standard for shafting substantially as described and as shown in the accompanying drawings.

In testimony of which invention I have hereunto set my hand.

ANTONIO C. PESSANO.
